UNITED STATES PATENT OFFICE.

WILLIAM P. MOTT, OF CHICAGO, ILLINOIS.

SPARK-TESTING DEVICE FOR GASOLINE ENGINES.

1,423,622.

Specification of Letters Patent. Patented July 25, 1923.

Application filed March 29, 1919. Serial No. 286,097.

To all whom it may concern:

Be it known that I, WILLIAM P. MOTT, a citizen of the United States, residing at Chicago, in the county of Cook and State 5 of Illinois, have invented certain new and useful Improvements in Spark-Testing Devices for Gasoline Engines, of which the following is a specification.

This invention relates to a spark testing 10 device for gasoline engines, and its purpose is to provide improved means for determining whether explosions are occurring regularly in all of the cylinders of a gasoline engine or whether sparks are passing between the terminals of the various spark 15 plugs. The principal object of the invention is to provide a simple and efficient testing switch which may be inserted in the circuit of the spark plug and opened when desired to determine whether the circuit is being completed through the spark plug. This testing switch comprises a relatively 20 small insulating member having mounted therein a movable blade, the insulating member being capable of being directly attached to the binding post on the top of a spark plug. Several of these switches may be combined in a composite testing device 25 adapted to be located on the dash-board of an automobile or the like.

These and other features of the invention will be understood more clearly from the following specification, taken with the accompanying drawings, in which certain embodiments are illustrated.

In the drawings—

Figure 1 shows the improved testing switch mounted in position on an engine cylinder with the circuit of the spark plug 40 represented diagrammatically;

Fig. 2 shows an enlarged side elevation of the spark plug and the testing switch;

Fig. 3 shows a sectional view taken on the line 3—3 of Fig. 2;

Fig. 4 shows a side elevation of a modified form of the invention in which several testing switches are mounted in a group on a single insulating base;

Fig. 5 shows a sectional view on the line 50 5—5 of Fig. 4.

In the drawings the spark plug 10 has a lower threaded portion 10^a adapted to engage the usual aperture in the upper part of the engine cylinder 11. The threaded 55 binding post 12 extends upwardly from the upper part of the spark plug and carries the

usual nuts 13 between which the electric conductor of the ignition circuit is ordinarily connected. In Fig. 1 this conductor 14 is shown extending to a battery or other source 60 of electric current 15, the other terminal of which is connected to a conductor 16 leading to the engine frame or other suitable part of the construction, whereby a return circuit to the other terminal of the spark plug is 65 formed.

Instead of connecting the conductor 14 directly to the binding post 12, the present invention makes use of an intermediate testing switch designated generally by the numeral 18. This switch comprises an insulating base 19 formed preferably of insulating fibre or the like and having a circular shape with a central circular aperture 20 extending therethrough. The lower portion of the 75 ring shaped insulating base 19 is provided with a threaded aperture 21 which is adapted to engage the threaded binding post 12, the binding post 12 extending upwardly into the aperture 20. A slot 22 extends downwardly 80 from the upper part of the insulating base, and this slot is adapted to contain a switch blade 23 of conducting material having an insulating handle 23^a. The upper edge of the blade is preferably shaped to conform to 85 the contour of the insulating base when the switch is closed, and the lower edge of the blade extends into the aperture 20 and is adapted to engage the upper end of the binding post 12. The blade is pivotally 90 mounted on a bolt or screw 24 which is adapted to be engaged by the nuts 25 and 26 between which the conductor 14 is adapted to be clamped. When the switch is closed, the electric current passes from the conductor 14 through the switch blade 23 to the binding post 12, which leads to one terminal 95 of the spark gap. The blade of the switch closely fits the slot 22 and is held in any desired adjusted position by the frictional contact of the walls of the slot.

In the operation of the invention, one of the switches 18 is mounted on each spark plug carried by a cylinder of the engine, and these switches are normally closed to complete the electric circuit for each cylinder. If any cylinder is "missing," or for any other reason it is desired to test the sparks in the various cylinders, the switches 23 may be elevated separately or in groups, and as 110 each switch is opened, the spark passing between the lower edge of the blade and the

upper end of the adjacent binding post 12 will indicate whether a circuit is passing through the gap of the spark plug or whether the circuit is otherwise defective. By regulating the amount of opening of the switch, the strength of the spark produced by the plug can be determined.

Instead of mounting individual switches 18 on the several cylinders beneath the hood 10 of the automobile, for example, the switches may be formed in a group, as illustrated in Figs. 4 and 5. In this embodiment a single insulating base 30 of rectangular cross-section is provided with a longitudinally extending slot 31 which extends downwardly from the upper side thereof and completely through the insulating base from end to end. A series of circular apertures 32 extend transversely through the base 30 with their 20 lower walls in alignment with the lower wall of the slot 31. Switch blades 33 of conducting material are mounted in the slot 31 and provided with insulating handles 33^a by which they may be opened and closed. 25 The switch blades 33 are of angular form and are pivoted on bolts or screws 35 which extend through the insulating base between the holes 32. The projecting ends of the screws 35 are engaged by nuts 36 and 37 between which the respective conductors 14 are adapted to be clamped. A pair of spring switch blades or plates 38 of conducting material extend upwardly into each of the apertures 33 through suitable holes 39 which are 35 formed through the lower wall of the insulating base. These switch blades are provided with angularly disposed arms which are held in position with respect to the base by screws 40. These screws 40 serve also to secure the 40 conductors 14^a in electrical connection with the blades 38. The conductors 14^a lead to the binding posts 12 of the spark plugs, so that one of the switches 33 is included in circuit with each of the spark plugs of the 45 engine. The blades 33 are normally in the position shown in Fig. 4, but when it is desired to test any of the plugs, they may be tilted upwardly in order to open any desired switch, thereby determining whether 50 a current is passing through the circuit of each switch plug. In each form of the invention, the slots which are cut in the fibre insulating base are preferably narrow and adapted to cause a tight frictional engagement 55 with the lateral faces of the switch blades, so that the switches are normally held in closed positions by the frictional engagement of the switch blades with the contacting insulating walls. The form of 60 the invention illustrated in Figs. 4 and 5 has the advantage that it may be mounted on the dash-board of the automobile, thereby permitting the driver to test the circuits of the engine cylinders without leaving his 65 seat.

Although certain embodiments of the invention have been shown and described for purposes of illustration, it will be understood that the improvement may be constructed in various different forms without departing from the scope of the appended claims.

What I claim is:

1. The combination in a switch of a metallic terminal, an insulating member connected to said terminal and having a slot therein, and a movable switch blade carried by said insulating member and movable into said slot to engage said metallic terminal. 75
2. The combination with a threaded terminal, of an insulating member having a threaded engagement with said terminal, said insulating member having an aperture therethrough into which said terminal is adapted to project, a switch blade mounted 80 on said insulating member and adapted to contact with said terminal within said aperture, and means for connecting said switch blade in a circuit. 85
3. The combination with a projecting terminal, of an insulating member of circular form mounted on said terminal, said insulating member having an aperture therethrough and being slotted transversely to said aperture, a switch blade mounted in said slot and 90 adapted to engage said terminal within said aperture, and means for connecting said blade in a circuit. 95
4. The combination with a threaded binding post, of a ring-shaped insulating member provided with a threaded aperture through one side thereof adapted to engage said binding post, said binding post being adapted to project into the central aperture of said insulating member, said insulating member being slotted transversely to its 100 central aperture, a switch blade movably mounted in and closely fitting said slot, said blade being adapted to engage said post and means for connecting said blades in a circuit. 110
5. The combination with a threaded terminal, of a ring-shaped insulating member provided with a threaded aperture through one side thereof adapted to engage said terminal, said terminal being adapted to project into the central aperture of said insulating member, said insulating member being slotted transversely to its central aperture, a switch blade mounted in and closely 115 fitting said slot, and adapted to engage said terminal, a connecting member extending through said insulating member and having said switch blade pivotally mounted thereon, and means for forming an electrical connection with said connecting member. 120

In testimony whereof, I have subscribed my name.

WILLIAM P. MOTT.
